MANIFOLD BILL BOOK

Roger L. Connor, Athens, Ohio, assignor to The
McBee Company, Athens, Ohio, a corporation
of Ohio

Application November 8, 1932. Serial No. 641,720

2 Claims. (Cl. 282—27)

My invention relates to that class of multiple forms which are intended for use where certain information typed on the outer leaf of the book is omitted from other sheets.

5 My invention more specifically relates to a new and improved form of bill to be used for public service corporations. It is well known that in the offices of many public service corporations (gas, power and water utilities) the accounts with their 10 consumers are handled without posting the various charges to ledgers. The method employed is familiarly known as the "Stub Plan". Under this plan the monthly bill to the consumer is usually made up in an original copy form comprised of three sections, the consumer's bill copy 15 (which is the extreme left section, a Cashier's Coupon (which is the middle section) and the Ledger Stub (the extreme right section). The combination bill forms are usually posted on book-keeping machines that are designed to automatically repeat-print the data pertaining to the charge to all three sections of the bill. Obviously 20 a good percentage of the time required to post the bills is consumed by the machine while it is making the several automatic operations necessary to re-print to the other two sections of the bill, the information that was written by the operator on the first section.

Either before the bills are posted or after, the 25 bills must be addressed for delivery or mailing. This is usually done on addressing machines of the embossed plate type (addressograph, etc.) although they may be addressed on the typewriter. Regardless of the means employed it is necessary 30 that the name and address of the consumer appear on at least two sections of the bill form (the consumer's bill and the ledger stub). This means at least two addressing operations.

After the bills have been addressed and posted 35 the ledger stubs must be torn away for filing before the bills can be delivered or mailed. These stubs comprise the accounts receivable ledger of the company.

If the bills are mailed it is necessary to place 40 them in envelopes. "Window" envelopes are usually employed to eliminate the added labor of addressing envelopes but there still remains the expense of inserting the bills and sealing the envelopes, plus the cost of envelopes.

45 My invention has for its object to provide a manifold bill book which will possess the following advantages:

50 1. All repeat printing of the bookkeeping machine is eliminated. This will materially increase the speed of billing.

2. Bills will be addressed only once for all copies. This too, will materially increase the speed of preparing bills for delivery or mailing.

3. If bills are mailed it will not be necessary to insert bills in envelopes. No envelopes are used 60 with my new and improved bill form. This will save much time in preparing the bills for mailing and save the cost of envelopes.

My means of accomplishing the foregoing objects may be more readily understood by having 65 reference to the accompanying drawings which are hereunto annexed and made a part hereof, in which

Fig. 1 is a perspective view of the complete book; 70

Fig. 2 is a plan view of the ledger strip;

Fig. 3 is a plan view of the obverse side thereof;

Fig. 4 is a plan view of the bill strip; and

Fig. 5 is a plan view of the obverse side of the same. Similar reference numerals refer to similar 75 parts throughout the entire description.

As shown in the drawings, the bill book is preferably made up of two separate strips adapted to be folded upon themselves. One of which consists of two folds 1 and 2, the other consisting 80 of three folds, 3, 4, and 5. These two strips when assembled, are interleaved as clearly seen in Fig. 1, in such a manner that the addressing and posting operations cause the required information to be written on all copies where desired and not to 85 appear on any copies upon which it is not desired. The backs of sheets are provided with carbon spots of a desired area to transfer or copy the information on such copies as it is desired to have the information appear on. 90

The assembled books are delivered to the book-keeping department in folded or book form and correctly interleaved, that is, with leaf 2 inserted between leaves 3 and 4 and they remain in this condition until the bills are posted and addressed 95 preparatory to mailing. With the carbon spots located as shown, it will be clearly seen that addressing the book will produce carbon copies of

the name and address which will appear on the ledger stub 1, the mailing cover or flap 3, the 100 cashiers coupon 4 and the consumer's bill 5. Posting the required information and amounts of the charges to the book on the bookkeeping machines will cause carbon copies to appear on the ledger stub 1, the cashiers coupon 4 and the consumer's 105 bill 5.

After the book has been addressed and posted the ledger stub or leaf 1 is removed and the leaf 2 is torn away along the perforations 6 provided for that purpose and thrown away since it is of no 110

further value. The ledger leaf 1 is then ready for filing in the regular order or manner. Obviously the removal of the strip containing leaves 1 and 2 leaves the remaining stubs still folded in 5 the manner originally described.

A standard model gummed paper sealing machine (not shown) may then be employed to seal the top edges of these leaves containing the copies. I refer to such machines as they are standard 10 equipment well known and will seal the books at a rate of approximately 100 per minute. It will be apparent that any manner of sealing or fastening the leaves of the books for mailing may be employed without departing from the scope of my 15 invention. As soon as they are sealed they are ready for deposit in the mail without any further operation being required.

Although I have shown a specific form and location for the carbon spots as well as the printed 20 form, it is to be understood that such showing is merely to illustrate a concrete embodiment of my invention and is not to be construed in any sense as limitation for it is clear that the printed form will vary with the requirements of the individual company using the books and also the 25 areas and locations of the carbon spots will vary as the type or form is varied.

Having described my invention what I regard as new and desire to secure by Letters Patent is:

30 1. A manifold and mailing bill comprising a ledger strip formed of two leaves, one of which has on its obverse surface a number of suitably indicated spaces to receive required data and a blank space below said indicated spaces, a carbon spot on the reverse surface of said leaf back of said blank space, the obverse surface of the other leaf being blank but having carbon spots on its reverse surface, one of which spots is adapted 35 to register with the carbon spot, and the other

40

with the indicated spaces on the first-named leaf, a bill strip formed by a center and two end leaves, one end leaf being blank and adapted to be interleaved with the ledger leaves, the other end leaf having one surface adapted to register with the obverse surface of the first-named leaf of the ledger strip and having carbon spots on its reverse surface adapted to register with the indicated spaces and the blank space on said ledger strip, the center leaf having a corresponding number of suitably indicated spaces in position to receive the data from the first leaf. 80

2. A manifold and mailing bill comprising a bill strip adapted to be folded to form three leaves, a center and two end leaves and a ledger strip adapted to be folded to form two leaves, one of which is adapted to be interleaved between one end leaf and the other end leaf of the bill strip, one leaf of the ledger strip having on its obverse surface a number of suitably indicated spaces to receive required data and a blank space below said indicated spaces, a carbon spot on the reverse surface of said leaf back of said blank space, the obverse surface of the other leaf being blank but having carbon spots on its reverse surface, one of which spots is adapted to register with the carbon spot and the other with the indicated spaces on the outer leaf of the ledger strip, one end leaf of the bill strip being blank and adapted to be placed intermediate the ledger leaves, the other end leaf having one surface adapted to register with the obverse surface of the outer leaf of the ledger strip and having carbon spots on its reverse surface adapted to register with the indicated spaces and the blank space on said ledger strip, the center leaf having a corresponding number of suitably indicated spaces in position to receive the data from the first leaf. 90
